[57] CLAIM

The ornamental design for jewelry display, as shown and described.

DESCRIPTION

FIG. 1 is a perspective view of my new design showing a fabric sheet to which a variety of jewelry may be attached; FIG. 2 is a side elevational view thereof; FIG. 3 is a front elevational view thereof; FIG. 4 is a rear elevational view thereof; FIG. 5 is a top plan view thereof; and, FIG. 6 is a bottom plan view thereof.

The jewelry and pockets extending laterally across the bottom of the sheet are for illustrative purposes only and are not intended to form any part of my claimed design.
